G. L. CHATFIELD.
BALL RELEASE FOR GAME APPARATUS.
APPLICATION FILED JUNE 30, 1917.

1,270,595.

Patented June 25, 1918.

UNITED STATES PATENT OFFICE.

GEORGE L. CHATFIELD, OF INDIANAPOLIS, INDIANA, ASSIGNOR TO BRIANT MANUFACTURING COMPANY, OF INDIANAPOLIS, INDIANA, A CORPORATION.

BALL-RELEASE FOR GAME APPARATUS.

1,270,595.

Specification of Letters Patent. Patented June 25, 1918.

Application filed June 30, 1917. Serial No. 177,870.

To all whom it may concern:

Be it known that I, GEORGE L. CHATFIELD, a citizen of the United States, residing at Indianapolis, in the county of Marion and State of Indiana, have invented certain new and useful Improvements in Ball-Releases for Game Apparatus, of which the following is a specification.

This invention relates to a device for releasing a determined number of balls for that class of game apparatuses employing an inclined alley upon which balls are pitched by a player to produce the highest possible score with an allotted number of balls; and one of the objects of the invention consists in the provision of certain means whereby, after the spent balls have been collected together at the player's end of the alley, a determined number of balls allotted 20 each player can be delivered to him gratis or at a fixed rate of charge, this depending whether the apparatus is installed for producing a source of revenue or not.

A further object of the invention consists 25 in the provision of a ball releasing device for game apparatuses which is simple in construction, efficient in operation and economical to manufacture.

I accomplish the above objects of the invention, and such others as may appear from a perusal of the specification and claims, by means of the construction illustrated in the accompanying drawings, forming a part hereof, in which—

35 Figure 1 is a fragmentary detail view in side elevation of the player's end of the game apparatus, showing the position occupied by my invention. Fig. 2 is a cross sectional view, on an enlarged scale, on the line 2—2 in Fig. 3. Fig. 3 is a fragmentary detail view partly in top plan of the alley and partly in section showing my invention exposed.

Referring to the drawings, 10 represents 45 the frame-work of the apparatus for keeping the balls within prescribed limits, and 11 a floor upon which the balls are rolled by the players. Alley floor 11 is elevated at its discharge end so as to return the spent balls to 50 the player's end by gravity. When a ball 12 is pitched and leaves the discharge end of floor 11 it returns to the player's end of the alley in a suitable race-way 15 located beneath floor 11. In this position balls 12 are 55 out of reach of the players for the reason

that race-way 15 is inclosed by the frame-work of the apparatus. The object of the present invention is to uniformly remove a determined number of balls from the balls collected in race-way 15 and deliver them to 60 the player as fast as he uses them. By means of this arrangement one player can take no advantage of another player, which would be possible if a greater number of balls were delivered to one player than to 65 another. To accomplish the above result, I sever race-way 15 transversely at A and B so as to provide a movable section which is designated 18, this movable section 18 being 70 of a length to coincide with the combined diameters of the number of balls allotted each player, which in the present case, is ten balls. Arranged adjacent and parallel with movable section 18 is a secondary ball receiving race-way 20 adapted to receive 75 the balls discharged from the movable section 18. Section 18 is hingedly secured to a fixed parting-rail 17 by means of the hinges 22. As all of the spent balls re-turned in race-way 15 are arranged in a 80 column *seriatim*, I provide a stop-block 16 in race-way 15, and adjacent to the lower end of movable section 18, thereby establishing a point for uniformly starting the column of balls collected in race-way 15 to 85 be dumped into the ball receiving race-way 20. Section 18 is provided with a fixed actuator-arm 25 having an eye 26 of considerable size in its free end, the said eye making a loose fitting coupling with the 90 crank-arm 27 of rock-shaft 28 which extends transversely through the side wall of the apparatus structure. The outer end of rock-shaft 28 preferably engages a crank-arm 29, and by means of a connecting-rod 95 30 said crank-arm is connected and actuated by a hand-lever 32 arranged externally of the frame and nearer the players' end of the alley. It will be readily understood, and especially so when examining the dotted 100 position of the parts in Fig. 2, that when hand-lever 32 is moved in the proper direction, rock-shaft 28 will move crank-arm 27 a distance to sufficiently depress fixed arm 25 so as to elevate movable section 18 to a 105 position to cause the balls carried in the latter to be dumped into receiving race-way 20. From race-way 20 the balls are fed into an exterior pocket 35 as fast as the player utilizes them.

To prevent movable section 18 from being operated a second time before the receiving section 20 is free of balls, which would enable one player to receive a greater number of balls than his allotted number, I provide a rocker-arm 40 which extends through the side of the frame and terminates in a right-angle arm having its end flattened, as at 41, adapted to rest squarely upon the balls 12 in the raceway 20, below. Rocker-arm 20 is provided on its outer end with a lever 42 through which it is oscillated from the hand-lever 32 by means of a connecting-bar 45. When hand-lever 32 is moved so as to cause race-way 18 to dump balls 12 into race-way 20, flattened end 41 of rocker-arm 40 will be depressed sufficiently into race-way 20 to form a temporary stop and prevent any of the newly delivered balls from rolling out into pocket 35. After the balls are discharged from race-way 18, hand-lever 32 is actuated to return section 18 to normal position, at the same time the flattened end of rocker-arm 40 is elevated to allow the newly delivered balls to move toward pocket 35. The line of balls in race-way 20 now extends under the flattened end 41 of rocker-arm 40 and these balls act as a stop to prevent hand-lever 32 from being operated until the balls in race-way 20 are exhausted, thereby preventing a player from receiving a number of balls in excess of his allotment.

If it is desired to operate the game for revenue, a suitable coin controlling device 50 can be employed for controlling the movement of hand-lever 32 by means of a connecting link 51.

Having thus fully described my said invention, what I desire to secure by Letters Patent, is—

1. The combination with a game apparatus including an alley for rolling the balls, of a ball race-way comprising a fixed and a movable section for returning the spent balls to the player end of the alley, and means for oscillating the movable section for discharging the balls from the latter.

2. The combination with a game apparatus including an alley for rolling the balls, of a ball race-way comprising a fixed and a movable section for returning the spent balls to the player end of the alley, means for pivotally mounting said movable section of the race-way, and means for oscillating the movable section for discharging the balls from the latter.

3. The combination with a game apparatus including an alley for the pitched balls, of a ball return race-way comprising a fixed and a movable section, means for arresting the returning balls at a determined position, and means arranged near the player end of the alley for actuating the movable race-way for discharging the balls therefrom.

4. The combination with a game apparatus including an alley for the pitched balls, of a ball return race-way comprising a fixed and a movable section, means for arresting the returning balls at a determined position, and means arranged near the player end of the alley for actuating the movable race-way for discharging the balls transversely therefrom.

5. The combination with a game apparatus including an alley for the pitched balls, of a ball return race-way comprising a fixed and a movable section, means for pivotally mounting said movable section, a ball receiving section arranged adjacently to said movable section, and means for oscillating the movable section for discharging the balls from the latter into said receiving race-way.

6. The combination with a game apparatus including an alley for the pitched balls, of a ball return race-way comprising a fixed and a movable section, means for pivotally mounting said movable section, a ball receiving race-way arranged adjacently of said movable section, a movable actuator for oscillating said movable section for dumping the balls therefrom into the receiving race-way, and means engaging the dumped balls in the receiving race-way for locking said movable actuator.

7. The combination with a game apparatus including an alley for the pitched balls, of a ball return race-way comprising a fixed and a movable section, means for pivotally mounting said movable section, a ball receiving section arranged adjacently to said movable section, means for oscillating said movable section for dumping the balls from the latter into the receiving race-way, and a pocket arranged exteriorly of the apparatus and communicating with the end of the ball receiving race-way for rendering the balls in the latter accessible to the player.

In witness whereof I have hereunto set my hand and seal at Indianapolis, Indiana.

GEORGE L. CHATFIELD. [L. S.]
